(57) CLAIM

The ornamental design for a luggage, as shown and described.

DESCRIPTION

FIG. 1 is a perspective view of a first embodiment of luggage showing our new design;

FIG. 2 is a front view thereof;

FIG. 3 is a back view thereof;

FIG. 4 is a right side view thereof;

FIG. 5 is a left side view thereof;

FIG. 6 is an enlarged view of a portion of FIG. 5;

FIG. 7 is a top view thereof;

FIG. 8 is a bottom view thereof;

FIG. 9 is a perspective view of a second embodiment thereof;

FIG. 10 is a front view of FIG. 9;

FIG. 11 is a back view of FIG. 9;

FIG. 12 is a right side view of FIG. 9;

FIG. 13 is a left side view of FIG. 9;

FIG. 14 is an enlarged view of a portion of FIG. 13;

FIG. 15 is a top view of FIG. 9; and,

FIG. 16 is a bottom view of FIG. 9.

The dash-dash-dash broken lines shown in the drawings are included for purposes of illustrating portions of the luggage and form no part of the claimed design. The dash-dot-dash broken lines shown in the drawings depict the boundary of the claim and form no part of the claim.

1 Claim, 12 Drawing Sheets

Fig. 6
